SWING

James E. Pippin, Fredonia, Kans.

Application October 23, 1940, Serial No. 362,385

2 Claims. (Cl. 155—63)

My invention relates to improvements in a swing, and has for its principal object a means to produce oscillatory movement by occupants carried thereby.

A further object of my invention is to provide a cushion for each end of the seating plank to avoid an injurious stroke upon children should they approach within the swinging path of the plank.

A still further object of my invention is to construct a swing in such a way as to maintain practically a horizontal position of the seating plank.

A still further object of my invention is to provide a swing having three pendant supporting means, one of which is centrally disposed whereby a pair of carrying planks are supported and aligned longitudinally, and a link means to hingedly connect the inner confronting ends of the planks, and a swinging motion produced by manipulating of the pendant support.

These and other objects will hereinafter be more fully explained, reference being had to the accompanying drawings forming a part of this specification, in which like characters will apply to like parts in the different views.

Referring to the drawings:

Fig. 1 is a plan view of the swing.

Fig. 2 is a reduced side view of the swing in operation.

Fig. 3 is an end view of Fig. 1.

Fig. 4 is an enlarged fragmentary view of the plank and cushion, partly in section.

Fig. 5 is a side view of the swing, the pendant supporting means partly broken away, and one swung position shown by dotted lines.

Fig. 6 is a view illustrating a modified method of connecting the saddle.

Fig. 7 is a side view of the saddle, and portion of the plank.

My invention herein disclosed consists of a pair of patron carrying planks 1, longitudinally aligned, the outer ends of which are pendants carried by their respective cables 2, the lower ends of said cables being attached to their respective outer ends of the planks by eye bolts 3 extending through the planks, while the upper end of each cable is carried by an eye screw 4 engaging in a ceiling 5, or the like, or a beam appropriately elevated and braced as carrying means for the swing.

Centrally positioned between the planks is a vertically disposed standard 6 having a foot rod 7 transversely carried at the lower end thereof, and a similar rod 8 secured to the upper end of

the standard as a grip for the hands of an occupant of the swing, last said rod to function as carrying means for the standard and to which are attached cables 9 as pendant supporting means for the standard and inner ends of the patron carrying planks.

Positioned substantially in the center of said standard is a link consisting of two oppositely disposed elements 10 that are secured to the standard by a bolt 11 passing therethrough and through each of said elements and being tensioned by a nut 12 threadedly engaging on the bolt, each outer end of said elements being spaced apart and apertured to receive apertured tongues 13, respectively, pivotedly carried therebetween and being rockably secured by bolts 14, each tongue being twisted through an arc of ninety degrees whereby the outer end will function as carrying means for the inner ends of said patron carrying planks and being secured thereto by bolts 15; being so connected the planks are free to swing horizontally while their inner or adjacent ends of said planks are rocked oppositely by the seesaw movement of the link, one position of which is shown at 10 in Fig. 2.

Each of said planks have a saddle 16 adjustably carried thereby, the adjustment being longitudinally of the plank by sliding the saddle to accommodate the patron and being secured stationarily by bolts 17 passing through the plank and saddle, there being one at each end of the saddle, and the said plank has a plurality of apertures 18 spaced therealong through which the bolts will engage, selectively.

In Figs. 6 and 7 is illustrated a modified method of securing the saddle and retaining the same on the plank which is accomplished through the medium of a pair of clips 19 and 20, that are secured to their respective ends of the saddle,

clip 20 having sufficient play vertically for rocking movement of the saddle, while clip 19 is of sufficient length to permit disengagement of the pin, the side of said clips being adapted to slideably engage in close contact with and along the edges of the plank to insure a longitudinal alignment of said saddle and plank. The latter arrangement of securing the saddle a selected point along the plank will eliminate the use of a wrench or other tools to make the adjustment.

Optionally secured to the outer end of each of said planks is a cushion which preferably is applied when the installation of the swing is in connection with kindergarten, the cushion being to avoid a severe rigid stroke upon a child when the swing is in motion, said cushion preferably

being of sponge rubber 22 directly applied to the end of the plank by an efficient securing means thereto, or the sponge rubber may be positioned in a flexing container 23 of leather, canvas or the like, having a neck 24 outwardly extending to engage about the end of the plank and being secured by headed tacks 25, but such restriction may not apply to municipal play grounds, but not an objectionable feature in any instance.

It will now be seen how a swing thus constructed may be operated by occupants as shown in Fig. 2, in which view occupant A by a thrust of the feet on the lower rod and by a pull of the hands on the upper rod will slant its cables from a vertical plane creating a tension to move the swing the direction of which the said occupant is confronting or opposite the downward slant of the cable as said cable is a pulling means to create momentum, while occupant B is releasing tension on the lower rod and may exert a thrust on the upper rod by the hands and vice versa to swing the opposite direction, and so to work up a desired oscillatory swinging movement. The swinging momentum will decrease gradually to idleness when the manual rock of the standard is omitted.

Such modifications may be made in the construction of the swing as lie within the scope of the appended claims.

Having fully described my invention what I claim as new and desire to secure by Letters Patent is:

1. In a swing of the class described comprising a standard vertically disposed and having a hand rod passing therethrough adjacent its upper end and another rod passing therethrough adjacent its lower end as a foot rod, a link secured to the standard intermediate said rods and outwardly extending from opposite sides of the standard transverse to the rods, a pair of beams having one end of each hinged to its respective end of 5 the link, each outer end of the hand rod and the free ends of each beam having cables to pendants carry the same and suitable means to which the upper ends of the cables are secured, all as and for the purpose specified.
- 10 2. In a swing, a standard vertically disposed and having a cross rod secured thereto adjacent its upper end and another cross rod secured to the standard adjacent its lower end and a pair of cables having one end of each attached to the upper cross rod and the other ends of said cables being secured to an upper support as pendant carrying means for the standard, an elongated link secured to the standard between said rods and being transverse thereto, each end portion 20 of the link extending outward from the standard to be engaged by the confronting ends of a pair of seat carrying beams hingedly connected thereto while the other ends of said beams are pendants carried by cables.
